COMBINED SPEAKER AND HEATER UNIT

Terrence J. Mulligan, 2044B Best Place, Aurora, Ill., and
John K. Morrison, 618 S. 4th St., Aurora, Ill. 60505

Filed Sept. 1, 1967, Ser. No. 8,453

Term of patent 14 years

(Cl. D26—14)

Fig 1

Fig 2

Fig 3

Fig 4

Fig 5

FIGURE 1 is a perspective view taken from the front and one side of a combined speaker and heater unit embodying our new design.

FIGURE 2 is a perspective view taken from the rear and a second side of the speaker and heater unit.

FIGURE 3 is a front elevational view of the speaker and heater unit.

FIGURE 4 is a rear elevational view of the speaker and heater unit.

FIGURE 5 is a bottom view of the combined speaker and heater unit.

The dominant features of our design reside in the portions shown in full lines in the figures.

We claim:

The ornamental design for a combined speaker and heater unit, as shown and described.
